UNITED STATES PATENT OFFICE.

HENRY D. HIBBARD, OF PLAINFIELD, NEW JERSEY, ASSIGNOR TO MANGANESE STEEL SAFE COMPANY, OF NEW YORK, N. Y., A CORPORATION OF NEW JERSEY.

GRINDING-MACHINE.

SPECIFICATION forming part of Letters Patent No. 741,336, dated October 13, 1903.

Application filed June 21, 1902. Serial No. 112,571. (No model.)

To all whom it may concern:

Be it known that I, HENRY D. HIBBARD, a citizen of the United States, residing in Plainfield, in the county of Union and State of New Jersey, have invented certain new and useful Improvements in Grinding-Machines, of which the following is a specification.

My present invention relates to mechanism for finishing plane surfaces—such, for instance, as those on cast or wrought metal or other dense material. In the mechanism shown and described herein as an illustration of an embodiment of my invention, but which is in no wise intended to limit the application or uses of the latter, I have introduced certain instrumentalities which are more particularly adapted either to accurately finish surfaces which have previously been shaped by cutting-tools or to remove stock in order to properly shape the resultant surface, the term "finished" used herein being intended to apply to either of the operations mentioned. When used for the last-mentioned purpose, my invention will be found especially applicable for operation upon bodies composed of material whose hardness precludes the use of ordinary cutting-tools. Other uses of my invention will, however, readily suggest themselves to those skilled in the art to which it appertains.

In the mechanism shown I have introduced among other improvements a combination of a driving means with a driven stock-removing instrumentality, the first mentioned being rigidly connected with the member on which the other is mounted, both said driving means and said instrumentality being connectedly adjustable to the stock to be operated upon, so that the instrumentality may be adapted for use in different positions while maintaining one and the same relation with the driving means. By this means I avoid the necessity of readjusting belts or other power-communicating devices in order to adapt them to each change of position of the stock-removing instrumentality. Furthermore, in order to adapt my invention for use upon large and heavy bodies of material I have provided means for shifting both the driving and the driven members longitudi-

nally of the machine and have thereby avoided the necessity for mounting upon said machine the object which is to be operated upon. I also provide means for angularly adjusting the slides on which the stock-removing instrumentalities, which are herein shown as grinding-wheels, are mounted, and I thereby adapt my invention for operating upon parts which may be transversely angular relative to the plane of the ways of the machine. By providing a plurality of the angularly-adjustable slides and of the operative members and the arbors mounted on said slides a plurality of surfaces angular with each other may be operated upon at the sametime, and the means for moving several separate combinations of the members mentioned longitudinally of the machine may be common to all of said members.

In the machine shown and described herein as an illustration of one form of my invention two stock-removing instrumentalities in the form of grinding mechanisms are shown; but I do not limit myself to any particular form or number of such elements and in that respect, as in other matters of detail, may adapt my invention to the specific requirements of particular uses.

In the drawings, Figure 1 is a front elevation of a machine, parts of the shears being broken away. Fig. 2 is an end elevation thereof looking from the right of Fig. 1. Fig. 3 is a top plan view of the machine as shown in Fig. 1. Fig. 4 is a perspective elevation of a cross-rail. Fig. 5 is a similar view of a part of an angularly-adjustable plate. Fig. 6 is a perspective elevation of a detached grinding mechanism and of the driving elements thereof. Fig. 7 is a horizontal transverse section taken on the line A A, Fig. 1, certain parts being removed. Fig. 8 is a side elevation of a cross-rail, an angularly-adjustable plate, and a wheel-arbor slide, other parts, except a column, being removed. Figs. 9 and 10, respectively, illustrate different angular adjustments of a wheel-arbor and a slide on which it is mounted. Fig. 11 is a perspective view, looking from the left, Fig. 1, of a part of the machine-shears and of members mounted thereon. Figs. 12 and 13 are illus-

trations of a feed-rod and a detachable pivot connection combined therewith; and Fig. 14 is a perspective view, looking from the right, Fig. 1, of a part of the machine-shears and of members mounted thereon. Figs. 11 to 14, inclusive, are on a larger scale than the others.

Like reference-marks indicate like parts throughout the drawings.

- 10 On legs L L are mounted shears S, on which are formed ways, such as W, on which a carriage 2 may be mounted and be slid lengthwise of the machine. On the carriage 2 is erected a plurality of columns 3 3, herein shown as two in number, and is formed with ways 3' 3', on which cross-rails 4 4 may be severally mounted and slid toward and from the carriage 2 by means of elevating-screws 3" 3", journaled in the columns 3 3, respectively. Bevel gear-wheels 3''' are shown here-in mounted upon the outer ends of the screws 3" 3" and meshing with bevel-pinnions 3^b 3^b, mounted on shafts 3^a 3^a, which are journaled crosswise of the columns 3 3 and are severally furnished with hand-wheels 3^c 3^c. Each cross-rail 4 is transversely slotted, as at 4', near each end thereof. (See Fig. 4.) On a stud 4" on each cross-rail 4 is pivotally mounted an angularly-adjustable plate 5, into which may be tapped binding-bolts 5' 5', which pass through the slots 4' 4', and each has a head which may be engaged with the cross-rail 4, through which the bolts pass.

A graduated arc 4^a may be described on each cross-rail 4, the same being located in part in this instance upon a suitable projection on the rail, and an index-pointer 4^b is attached to the angularly-adjustable member 5 to indicate on the graduated arc 4^a the angle 40 formed by the adjustable member and the cross-rail. Ways 5" 5" are formed on the angularly-adjustable plates 5 5, respectively, on which slides 6 6 may be mounted to slide to and fro transversely of the machine. Arbors 7 7 are rotatably mounted in journal-boxes 6' 6', which may be bracketed to each slide 6, and on each arbor and near an end thereof, as shown, is mounted a suitable operative member, herein shown as a grinding-wheel 8.

A feed-screw shaft 9 is journaled in and lengthwise of each slide 6, and each engages a nut 9', secured to the corresponding pivoted plate 5. A hand-wheel 9" and a ratchet-wheel 9''' are fixed upon each feed-screw, and a spring-pressed double-acting pawl 10 (see more particularly Fig. 14) rocks on a pivot fixed on a slotted arm 10', and the latter in turn rocks on the feed-screw shaft 9. A 60 perforated clamp 11, shiftable in the slot 10' of the rocking arm 10', may be secured in position by a thumb-nut 11' and washer 11". A rocking pivot 12 may pass through the clamp 11 and be secured in place by jam-nuts 12' 12". The pivot 12 has a head 12" perforated transversely to receive a feed-rod 13, and the pivot may be slid lengthwise

of said rod, or the latter may be retained in any desired position in said pivot-body 12" by a set-screw 12'', herein shown as having a knurled head. The feed-rod 13 also passes through a guide 14, which is bracketed on a pivot 14', screwed into a lug attached to the carriage 2. Splines 13' 13', movable in splineways in a guide-sleeve 14, are attached to the feed-rod 13 to prevent it from rotating. At one end the rod 13 is attached radially to the curved foot 15, and it may be screwed into a hub 15', formed on the inner curved edge of said foot and retained in any desired position angularly of the axis of the hub 15' by a jam-nut 15". Situated on one side of the shears S is a slideway w, (see more particularly Fig. 14,) on which a feed-actuator 16 is adjustably mounted to slide lengthwise of the machine, the same being secured in position on the slideway w by a set-screw 16', which is tapped through the web of the feed-actuator and screws against the surface of the slideway w, thus binding the feed-actuator 16 against the inner faces of the slideway w. The feed-actuator 16 has an outer member 16", rigidly attached thereto and adapted in form and by its position to be engaged by and to lift the foot 15 of the feed-rod 13 when the latter, with the carriage 2, is moved in either direction longitudinally of the machine, as hereinafter related. While but one feed-actuator is shown, a plurality may be used, if necessary, and they, with a plurality of feet, such as 15, may be disposed in different planes of operation.

Mounted upon the slides 6 6, respectively, are shown pedestals P P, which support motors 20 20, and on the shafts of the latter are mounted pulleys 20' 20', which are respectively belted to pulleys 7' 7', severally mounted on the respective arbors 7.

While the elements as thus far described are more particularly adapted for operation upon bodies which may rest upon any suitable support apart from the machine proper, nevertheless I may so form all of said elements as to adapt them severally and collectively to operate upon parts which may be secured upon the shears of the machine. This I may effect, for instance, by arching the carriage 2 and by mounting the operative members, herein shown as grinding-wheels 8 8 between the arbor-journals, or by making a suitable adaptation of the elements and organization embraced in my invention I may operate simultaneously upon several parts, which may be mounted, respectively, in the several positions mentioned.

A leading member, which may be of any desired form, is shown herein as a screw-shaft 17, journaled at each end of the shears S and engaging a threaded nut 2^a, which is secured to the carriage 2. At one end the screw-shaft 17 is provided with a collar 17', fixed thereon and contacting with one end of a journal-box, and at the other end of said box the screw-shaft has a washer 17" and a pair of jam-nuts

17" 17", the latter being adjustable to prevent end play of the shaft 17. Near the other end of said shaft a loose pulley 18 is in this instance mounted thereon between two tight pulleys 18' 18', the latter serving as collars to retain the loose pulley in position axially of the shaft. A pair of belts, one of which, 19, is straight and the other, 19', is crossed, are used to communicate power to the pulleys 18' 18' from a drum-pulley 20", mounted on the rotatable shaft of a power-supplying device 20^a, which may be similar to those hereinbefore referred to and may be similarly mounted on a pedestal P. The belts 19 19' may conveniently be shifted axially of the pulleys 18 18' by slotted arms 21' 21', through which they pass, (see more particularly Fig. 11,) the arms 21' 21' being rigidly secured to the reciprocatable bar 21, which is mounted in a bracket b, which is secured to a larger bracket B, which in turn is secured to the shears S and is furnished with an outriggered journal-bearing B' for the screw-shaft 17. At one end the bar 21 is pivoted to a rocker-arm 22", which in turn is pivoted in suitable supports by means of a rock-shaft 22, on which a second arm 22' is also mounted. The latter is pivotally connected with a reciprocatable bar 23, which may extend throughout the whole length of the shears S and be mounted in lugs secured to the latter and may also be supported in a lug 2^b, secured to the carriage 2. Adjustable stops, shown as collars 23' 23', each of which is furnished with a set-screw 23" 23", are mounted on the reciprocatable bar 23, one at each side of the lug 2^b. In operation, assuming that a body to be surfaced has been properly positioned relative to the machine, (see, for instance, Fig. 2, where X may represent such a body with faces x x',) one wheel-arbor 7, with its slide 6, may be adjusted parallelly of the face x, and the other arbor and slide may be adjusted parallelly of the face x', said adjustments being readily effected by suitably swinging the angularly-adjustable members 5 5 on the pivot-studs 4" 4", respectively, according to indications read on the graduated arc, after which the members 5 5 may be secured in their respective positions by means of the binding-bolts 5' 5'. By rotating the hand-wheels 3^c 3^c the grinding-wheels 8 8 may be respectively either raised or lowered to the proper levels for operation on the faces x and x'. By rotating the hand-wheels 9" 9" the grinding-wheels may be brought to the proper position transversely of the body X to begin operations upon the latter. The feed-actuator set-screw 16' being loosened, the actuator may now be adjusted longitudinally of the machine, so that the member 16" may properly engage the foot 15 of the feed-rod 13 adjacent to the end of the carriage-traverse, the actuator 16 being thereafter retained in position by the set-screw 16', as before related. The feed-rod 13 may now be secured in the pivot-head 12" after being either raised or lowered, as the case may

be, in order to secure thereby an adequate amount of motion of the arm 10', pawl 10, ratchet-wheel 9", and feed-screw shaft 9. If necessary, the clamp 11 may also be adjusted in the arm 10 to assist in effecting the object desired, which, as will readily be seen, is a proper feeding movement of the wheels 8 8, respectively, across the surfaces x and x'. Finally by properly adjusting the stop-collars 23' 23' on the reversing-bar 23 the operator may provide for a definite amount of movement of the carriage 2 between the operations of the lead-screw-reversing mechanism. If the motors 20 20 be now started, they will operate the stock-removing instrumentalities or grinding-wheels, and finally if the motor 20^a be started the wheels 8 8 will be reciprocated upon the stock longitudinally of the machine and be fed across it transversely of the machine.

Having described my invention, I claim—

1. In a machine for finishing plane surfaces, the combination of a rotatable stock-removing instrumentality whose axis is disposed transversely to the machine, means for angularly adjusting the axis in the plane transverse to the machine which passes through said axis, and means for removing said instrumentality to and fro in the direction of its adjusted axis. 90

2. In a machine for finishing plane surfaces, the combination of a rotatable stock-removing instrumentality movable both longitudinally and transversely of the machine and whose axis is disposed transverse to the line of such longitudinal movement, means for angularly adjusting the axis in the plane transverse to the line of said longitudinal movement, and means for moving said instrumentality to and fro in the direction of its adjusted axis. 105

3. In a machine for finishing plane surfaces, the combination of a rotatable stock-removing instrumentality adjustable vertically of the machine and movable both longitudinally and transversely thereof and whose axis is disposed transverse to the line of such longitudinal movement, means for angularly adjusting the axis in the plane transverse to the machine which passes through said axis, and means for moving said instrumentality to and fro in the direction of its adjusted axis. 110

4. In a machine for finishing plane surfaces, the combination of a supporting-bed, a feed-actuator adjustable longitudinally of the machine, a rotatable stock-removing instrumentality shiftable transversely of the machine 125 at an angle to the plane of the supporting-bed in the direction of its axis, and feed mechanism actuatable by the feed-actuator.

5. In a machine for finishing plane surfaces, the combination of a supporting-bed, a feed-actuator adjustable longitudinally of the machine, a rotatable stock-removing instrumentality adjustable vertically of the machine and whose axis may be adjusted in the plane trans-

verse to the machine which passes through its axis; and feed mechanism actuatable by the feed-actuator.

6. In a machine for finishing plane surfaces, the combination of a supporting-bed, a feed-actuator adjustable longitudinally of the machine, a rotatable stock-removing instrumentality adjustable vertically of the machine and movable both longitudinally of the machine and transversely thereof at an angle to the plane of the supporting-bed, and feed mechanism actuatable by the feed-actuator.

7. In a machine for finishing plane surfaces, the combination of a supporting-bed having horizontal ways, a carriage mounted thereon, a slide on the carriage angularly adjustable in a vertical plane and movable transversely of said bed in the line of its adjusted axis, a stock-removing instrumentality mounted on and movable with the slide, and a motor for said instrumentality mounted on and movable with the slide.

8. In a machine for finishing plane surfaces, the combination of a supporting-bed having horizontal ways, a carriage, a slide on the carriage adjustable vertically of the machine, a slide angularly adjustable in a vertical plane and movable transversely of said bed in the line of its adjustment, a rotatable stock-removing instrumentality mounted on and movable with the second-mentioned slide, and a motor for said instrumentality mounted on and movable with said angularly-adjustable slide.

9. In a machine for finishing plane surfaces, the combination of a slide mounted to move transversely of the machine and shiftable longitudinally thereof and angularly adjustable in a plane transverse to the machine, a stock-removing instrumentality mounted on and movable with the slide, and a motor mounted on and movable with the slide.

10. In a machine for finishing plane surfaces, the combination of a slide mounted to move transversely of the machine and adjustable vertically thereof and angularly adjustable in a plane transverse to the machine, a stock-removing instrumentality mounted on and movable with the slide, and a motor mounted on and movable with the slide.

11. In a machine for finishing plane surfaces, the combination of a slide movable both transversely and longitudinally of the machine; a rotatable stock-removing instrumentality mounted on and movable with the slide; a motor mounted on and movable with the slide; and means for communicating power from the motor to operate the stock-removing instrumentality.

12. In a machine for finishing plane surfaces, the combination of a slide mounted to move transversely of the machine and movable longitudinally thereof; and angularly adjustable in a plane transverse to the machine and parallel to such line of transverse movement; a stock - removing instrumentality mounted on and movable with the slide; a motor mounted on and movable with the slide;

and means for communicating power from the motor to operate the stock-removing instrumentality.

13. In a machine for finishing plane surfaces, the combination of a slide mounted to move transversely of the machine, adjustable vertically thereof and movable longitudinally thereof; and angularly adjustable in a plane transverse to the machine and parallel to such line of transverse movement; a stock-removing instrumentality mounted on and movable with the slide; a motor mounted on and movable with the slide; and means for communicating power from the motor to operate the stock-removing instrumentality.

14. In a machine for finishing plane surfaces, the combination of a slide mounted to move longitudinally thereof and transversely thereof in the direction of its angular adjustment in a plane transverse of the machine, a rotatable stock - removing instrumentality mounted on and movable with the slide, a motor mounted on and movable with the slide, means for communicating power from the motor to rotate the stock-removing instrumentality, means for moving the slide longitudinally and a feed mechanism for shifting it in said transverse direction.

15. In a machine for finishing plane surfaces, the combination of a slide mounted to move longitudinally thereof and transversely thereof in the line of its angular adjustment in a plane transverse to the machine, a rotatable stock-removing instrumentality mounted on and movable with the slide, a motor mounted on and movable with the slide, means for communicating power from the motor to rotate the stock-removing instrumentality, a screw for effecting the longitudinal movement of the slide, and adjustable feed mechanism for effecting its said transverse movement.

16. In a machine for finishing plane surfaces, the combination of a slide mounted to move transversely of the machine and movable both transversely and longitudinally thereof and angularly adjustable in a plane transverse to the machine and parallel to such line of transverse movement; a rotatable stock-removing instrumentality mounted on and movable with the slide; a motor mounted on and movable with the slide; and means for communicating power from the motor to rotate the stock-removing instrumentality.

17. In a machine for finishing plane surfaces, the combination of a slide mounted to move transversely of the machine, adjustable vertically thereof and reciprocatable longitudinally thereof and angularly adjustable in a plane transverse to the machine and parallel to such line of transverse movement; a rotatable stock-removing instrumentality mounted on and movable with the slide; a motor mounted on and movable with the slide; and means for communicating power from the motor to rotate the stock-removing instrumentality.

18. In a machine for finishing plane surfaces, the combination of a carriage reciprocatable longitudinally thereof and having columns disposed thereon; a cross-rail mounted on said columns and shiftable vertically thereof; a member pivoted on said cross-rail and angularly adjustable about an axis disposed in line with the direction of longitudinal reciprocation of the carriage; a slide mounted on the angularly-adjustable member and shiftable transversely of the machine; and a stock-removing instrumentality mounted on the slide. 5
19. In a machine for finishing plane surfaces, the combination of a carriage reciprocatable longitudinally thereof and having columns disposed thereon; a cross-rail mounted on said columns and shiftable vertically thereof; a member pivoted on said cross-rail and angularly adjustable about an axis disposed in line with the direction of longitudinal reciprocation of the carriage; a slide mounted on the angularly-adjustable member and shiftable transversely of the machine; and a stock-removing instrumentality mounted on and movable with the slide; a motor mounted on and movable with the slide; and means for communicating power from the motor to operate the stock-removing instrumentality. 10
20. In a machine for finishing plane surfaces, the combination of a carriage reciprocatable longitudinally thereof and having columns disposed thereon; a cross-rail mounted on said columns and shiftable vertically thereof; a member pivoted on said cross-rail and angularly adjustable about an axis disposed in line with the direction of longitudinal reciprocation of the carriage; a slide mounted on the angularly-adjustable member and shiftable transversely of the machine; a feed-actuator shiftable longitudinally of the machine; a stock-removing instrumentality mounted on the slide; and feed mechanism therefor actuatable by the feed-actuator. 15
21. In a machine for finishing plane surfaces, the combination of a carriage reciprocatable longitudinally thereof and having columns disposed thereon; a cross-rail mounted on said columns and shiftable vertically thereof; a member pivoted on said cross-rail and angularly adjustable about an axis disposed in line with the direction of longitudinal reciprocation of the carriage; a slide mounted on the angularly-adjustable member and reciprocatable transversely of the machine; a feed-actuator shiftable longitudinally of the machine; a stock - removing instrumentality mounted on the slide; feed mechanism therefor actuatable by the feed-actuator; a motor mounted on and movable with the slide; and means for communicating power from the motor to operate the stock-removing instrumentality. 20
22. In a machine for finishing plane surfaces, the combination of a carriage having columns disposed thereon; a cross-rail mounted on said columns and shiftable vertically thereof; a member pivoted on said cross-rail and angularly adjustable about an axis disposed in line with the direction of longitudinal reciprocation of the carriage; a slide mounted on the angularly-adjustable member and reciprocatable transversely of the machine; a feed-actuator shiftable longitudinally of the machine; a stock - removing instrumentality mounted on the slide; and feed mechanism therefor actuatable by the feed-actuator. 25
23. In a machine for finishing plane surfaces, the combination of a carriage having columns disposed thereon; mechanism for reciprocating the carriage longitudinally of the machine; a cross - rail mounted on the columns of the carriage and shiftable vertically thereof; a member pivoted on the cross-rail and angularly adjustable about an axis disposed in line with the direction of longitudinal reciprocation of the carriage; a slide mounted on the angularly-adjustable member; and a stock-removing instrumentality mounted on the slide. 30
24. In a machine for finishing plane surfaces, the combination of a carriage having columns disposed thereon; a cross-rail mounted on the columns and shiftable vertically thereof; an angularly-adjustable member pivoted on said cross-rail; a slide mounted on the angularly - adjustable member; a stock-removing instrumentality mounted on the slide; feed mechanism for shifting the slide transversely of the machine; a motor mounted on and movable with the slide; and means for communicating power from the motor to operate the stock-removing instrumentality. 35
25. In a machine for finishing plane surfaces; the combination of a carriage having columns disposed thereon; mechanism for reciprocating the carriage longitudinally of the machine; a cross-rail mounted on the columns of the carriage; an angularly-adjustable member pivoted on said cross-rail; a slide mounted on the angularly-adjustable member; a stock-removing instrumentality mounted on the slide; a motor mounted on and movable with the slide; and means for communicating power from the motor to operate the stock-removing instrumentality. 40
26. In a machine for finishing plane surfaces, the combination of a carriage having columns disposed thereon; mechanism for reciprocating the carriage longitudinally of the machine; a cross-rail mounted on the columns of the carriage; an angularly-adjustable member pivoted on said cross-rail; a slide mounted on the angularly-adjustable member; a stock-removing instrumentality mounted on the slide; and means for automatically reversing the mechanism for reciprocating the carriage longitudinally of the machine. 45
27. In a machine for finishing plane surfaces, the combination of a carriage having columns disposed thereon; a cross-rail mounted on said columns and shiftable vertically thereof; an angularly-adjustable member piv- 50

oted on said cross-rail; a slide mounted on the angularly-adjustable member; a feed-actuator shiftable longitudinally of the machine; a stock-removing instrumentality 5 mounted on the slide; and feed mechanism therefor actuatable by the feed-actuator.

28. In a machine for finishing plane surfaces, the combination of a plurality of rotatable stock-removing instrumentalities, and 10 means for angularly adjusting the several axes thereof transversely of the machine.

29. In a machine for finishing plane surfaces, the combination of a plurality of rotatable stock-removing instrumentalities sever- 15 ally adjustable vertically of the machine and severally shiftable transversely of the machine and reciprocatable longitudinally thereof; and means for angularly adjusting the respective axes of said instrumentalities trans- 20 versely of the machine.

30. In a machine for finishing plane surfaces, the combination of a feed-actuator adjustably shiftable longitudinally of the machine; a plurality of stock-removing instru- 25 mentalities, severally shiftable transversely of the machine; and a plurality of feed mechanisms for said instrumentalities, severally actuatable by the feed-actuator.

31. In a machine for finishing plane surfaces, the combination of a feed-actuator adjustably shiftable longitudinally of the machine; a plurality of rotatable stock-removing instrumentalities, severally adjustable vertically of the machine and movable both 35 longitudinally and transversely of the machine; and a plurality of feed mechanisms for said instrumentalities, severally actuatable by the feed-actuator.

32. In a machine for finishing plane surfaces, the combination of a plurality of slides severally shiftable transversely of the machine; a plurality of stock-removing instrumentalities severally mounted on and movable with the respective slides; a plurality of 45 motors severally mounted on and movable with the respective slides; and means for communicating power from the motors to operate the stock-removing instrumentalities.

33. In a machine for finishing plane surfaces, the combination of a plurality of angularly-adjustable slides severally mounted transversely of the machine, adjustable vertically thereof and movable both transversely and longitudinally thereof; a plurality of 50 stock-removing instrumentalities mounted on and movable with the respective slides; a plurality of motors severally mounted on and movable with the respective slides; and means for communicating power from the 55 motors to operate the stock-removing instrumentalities.

34. In a machine for finishing plane surfaces, the combination of a plurality of angularly-adjustable slides severally mounted 60 transversely thereof; a plurality of rotatable stock-removing instrumentalities severally

mounted on and movable with the respective slides; a plurality of motors severally mounted on and movable with the respective slides; and means for communicating power from 70 the motors to rotate the stock-removing instrumentalities.

35. In a machine for finishing plane surfaces, the combination of a plurality of angularly-adjustable slides severally mounted 75 transversely of the machine and adjustable vertically thereof; a plurality of rotatable stock-removing instrumentalities severally mounted on and movable with the respective slides; a plurality of motors severally mounted 80 on and movable with the respective slides; and means for communicating power from the motors to rotate the stock-removing instrumentalities.

36. In a machine for finishing plane surfaces, the combination of a plurality of slides severally adjusted vertically of the machine and shiftable transversely thereof; a plurality of rotatable stock-removing instrumentalities severally mounted on and movable 85 with the respective slides; a plurality of motors severally mounted on and movable with the respective slides; and means for communicating power from the motors to rotate the stock-removing instrumentalities. 95

37. In a machine for finishing plane surfaces, the combination of a plurality of angularly-adjustable slides severally mounted transversely of the machine and movable both transversely and longitudinally thereof 100 a plurality of rotatable stock-removing instrumentalities severally mounted on and movable with the respective slides; a plurality of motors severally mounted on and movable with the respective slides; and means 105 for communicating power from the motors to rotate the stock-removing instrumentalities.

38. In a machine for finishing plane surfaces, the combination of a plurality of angularly-adjustable slides severally mounted 110 transversely of the machine, adjustable vertically thereof and shiftable transversely thereof; a plurality of rotatable stock-removing instrumentalities severally mounted 115 on and movable with the respective slides; a plurality of motors severally mounted on and movable with the respective slides; and means for communicating power from the 120 motors to rotate the stock-removing instrumentalities.

39. In a machine for finishing plane surfaces, the combination of a carriage reciprocatable longitudinally thereof and having columns disposed thereon; a plurality of cross-rails mounted on said columns and severally shiftable vertically thereof; a plurality of angularly-adjustable members severally pivoted on the respective cross-rails; a plurality of slides severally mounted on the respective 125 angularly-adjustable members and shiftable transversely of the machine; and a plurality 130

of stock-removing instrumentalities severally mounted on the respective slides.

40. In a machine for finishing plane surfaces, the combination of a carriage reciprocable longitudinally thereof and having columns disposed thereon; a plurality of cross-rails mounted on said columns and severally shiftable vertically thereof; a plurality of angularly-adjustable members severally pivoted on the respective cross-rails; a plurality of slides severally mounted on the respective angularly-adjustable members and shiftable transversely of the machine; a plurality of stock-removing instrumentalities mounted on and movable with the respective slides; a plurality of motors severally mounted on and movable with the respective slides; and means for communicating power from the motors to operate the stock-removing instrumentalities.

20 41. In a machine for finishing plane surfaces, the combination of a carriage reciprocable longitudinally thereof and having columns disposed thereon; a plurality of cross-rails mounted on said columns and severally shiftable vertically thereof; a plurality of angularly-adjustable members severally pivoted on the respective cross-rails; a plurality of slides severally mounted on the respective angularly-adjustable members and shiftable transversely of the machine; a feed-actuator shiftable longitudinally of the machine; a plurality of stock-removing instrumentalities severally mounted on the respective slides; and feed mechanism therefor actuatable by the feed-actuator.

30 42. In a machine for finishing plane surfaces, the combination of a carriage having columns disposed thereon; a plurality of cross-rails mounted on said columns and severally shiftable vertically thereof; a plurality of angularly-adjustable members severally pivoted on the respective cross-rails; a plurality of slides severally mounted on the respective angularly-adjustable members; a plurality of stock-removing instrumentalities mounted on the respective slides; and feed mechanism for shifting the slides transversely of the machine.

40 43. In a machine for finishing plane surfaces, the combination of a carriage having columns disposed thereon; mechanism for reciprocating the carriage longitudinally of the machine; a plurality of cross-rails mounted on the columns of the carriage and severally shiftable vertically thereof; a plurality of angularly-adjustable members severally pivoted on the respective cross-rails; a plurality of slides severally mounted on the respective angularly-adjustable members; and a plurality of stock-removing instrumentalities severally mounted on the respective slides.

50 44. In a machine for finishing plane surfaces, the combination of a carriage having columns disposed thereon; mechanism for reciprocating the carriage longitudinally of the

machine; a plurality of cross-rails mounted on the columns of the carriage and severally shiftable vertically thereof; a plurality of angularly-adjustable members severally pivoted on the respective cross-rails; a plurality of slides severally mounted on the respective angularly-adjustable members; a plurality of stock-removing instrumentalities severally mounted on the respective slides; and feed mechanism for shifting the slides transversely of the machine.

50 45. In a machine for finishing plane surfaces, the combination of a carriage having columns disposed thereon; a plurality of cross-rails mounted on the columns and severally shiftable vertically thereof; a plurality of angularly-adjustable members severally pivoted on the respective cross-rails; a plurality of slides severally mounted on the angularly-adjustable members; a plurality of stock-removing instrumentalities severally mounted on the respective slides; feed mechanism for shifting the slides transversely of the machine; a plurality of motors severally mounted on and movable with the respective slides; and means for communicating power from the motors to operate the stock-removing instrumentalities.

60 46. In a machine for finishing plane surfaces; the combination of a carriage having columns disposed thereon; mechanism for reciprocating the carriage longitudinally of the machine; a plurality of cross-rails severally mounted on the columns of the carriage; a plurality of angularly-adjustable members severally pivoted on the respective cross-rails; a plurality of slides severally mounted on the respective angularly-adjustable members; a plurality of stock-removing instrumentalities severally mounted on the respective slides; a plurality of motors severally mounted on and movable with the respective slides; and means for communicating power from the motors to operate the stock-removing instrumentalities.

70 47. In a machine for finishing plane surfaces, the combination of a carriage having columns disposed thereon; mechanism for reciprocating the carriage longitudinally of the machine; a plurality of cross-rails severally mounted on the columns of the carriage; a plurality of angularly-adjustable members severally pivoted on the respective cross-rails; a plurality of slides severally mounted on the respective angularly-adjustable members; a plurality of stock-removing instrumentalities severally mounted on the respective slides; and means for automatically reversing the mechanism for reciprocating the carriage longitudinally of the machine.

80 48. In a machine for finishing plane surfaces, the combination of a carriage having columns disposed thereon; a plurality of cross-rails mounted on said columns and severally shiftable vertically thereof; a plurality

of angularly-adjustable members severally pivoted on the respective cross-rails; a plurality of slides severally mounted on the respective angularly-adjustable members; a feed-actuator shiftable longitudinally of the machine; a plurality of stock-removing instrumentalities severally mounted on the re-

spective slides; and feed mechanism for said instrumentalities actuatable by the feed-actuator.

HENRY D. HIBBARD.
